UNITED STATES PATENT OFFICE.

LEOPOLD LEER, OF NEW YORK, N. Y.

WRENCH.

1,113,903.

Specification of Letters Patent. Patented Oct. 13, 1914.

Application filed May 25, 1914. Serial No. 840,706.

To all whom it may concern:

Be it known that I, LEOPOLD LEER, a citizen of the United States, residing at the borough of Bronx, in the county of Bronx 5 and State of New York, have invented an Improvement in Wrenches, of which the following is a specification.

My invention relates to adjustable wrenches, and its object is to provide a tool 10 of a character applicable to all purposes for which such devices are employed, particularly useful in close quarters that cannot be reached by the ordinary wrenches, and also to lessen its cost and bulk or size.

15 The details of construction are hereinafter particularly described.

In the accompanying drawing: Figure 1 is a front elevation of the preferred form of my invention. Fig. 2 is a side view of 20 the same. Fig. 3 is a rear view of the same. Fig. 4 is a view similar to Fig. 2, with the auxiliary or interchangeable jaws removed. Fig. 5 is a section on the broken line α , α , of Fig. 2. Fig. 6 is a section on the broken 25 line γ , γ , of Fig. 4. Fig. 7 is a front elevation showing a modification with the handle broken away. Fig. 8 is a side view of the same, and Fig. 9 is a view similar to Fig. 8, but showing the auxiliary jaws attached. 30 In Fig. 1, the broken lines show the jaws fully extended and grasping a hexagonal nut.

Similar reference characters indicate like parts throughout the several views. 35 The stock and handle of my improved wrench are formed of one piece of metal. The elongated portion 10 is the handle. This has a right angle bend 11, a straight portion 12 parallel with the handle portion 40 and having a right angle bend 13 at its top. The bent portions 11 and 13 are thus spaced apart opposite each other. Each of these parts 11 and 13 are provided with an opening in alinement with each other, in which 45 is journaled a screw 14, that portion of which coming between the parts 11 and 13 is provided on one half with a right handed screw thread and on the other half with a left handed screw thread. On each end of 50 the screw 14 there is a knurled head 15. The straight portion 12 of the stock is provided with a longitudinal slot 16.

In the preferred form of my invention, 55 17, 17, indicate two adjustable jaws, the shanks 18 of which pass through and are slideable in the slot 16 of the part 12, each

of the shanks 18 being provided with a screw threaded hole to fit the threads on the screw 14. The jaws 17 thus have a simultaneous movement toward or away from 60 each other, according to the manipulation of the knurled heads 15. The gripping parts of the jaws are preferably made triangular so as to fit nuts of different shapes.

19, 19, designate two auxiliary jaws, 65 which are preferably somewhat larger than the jaws 17. These auxiliary jaws are provided with angular gripping surfaces, and are attached to the rear ends of the shanks 18 of the jaws 17, by screws 20; there being 70 screw threaded recesses 21 on the ends of the shanks 18 for this purpose. These auxiliary jaws are therefore interchangeable; one set may be removed and another set of different size or shape substituted, and 75 they are easily replaced if either or both jaws become worn or injured in use. Where the wrench is required for use in very close quarters, these auxiliary jaws may be detached from the wrench, as shown in Fig. 4. 80

In the modified forms shown in Figs. 7, 8 and 9, the stock and handle are made in one piece with the same bends shown in the other figures; but in this case there is only one adjustable jaw 17 and one sliding auxiliary jaw 19. In such case, the upper right angle bent portion 13 is made thicker to form an upper fixed jaw 22, with a gripping surface corresponding with that of the lower adjustable jaw, the upper auxiliary jaw 19 90 being removably secured to the upper end of the straight portion 12 by a screw or screws, in line with the fixed jaw 22. In this construction, only one of the knurled heads is required on the screw 14. The upper end of the screw having a smooth surface and journaled in an opening 24 in the part 13 in which it may be supported by a head 25, suitably secured to said end, there being a countersunk part surrounding said 100 opening 24 to receive said head.

It is customary, especially for drivers of motor vehicles, to carry a number of wrenches for use on nuts of different sizes and shapes, and it will be readily seen that 105 by the employment of my improved wrench, this necessity will be greatly, if not entirely, overcome.

I claim as my invention:

1. An adjustable wrench having a stock 110 consisting of a straight portion with a right-angled bend at each end thereof op-

- positely disposed, and an integral handle projecting from one of said bends parallel with said straight portion of the stock, a screw threaded shaft supported between and 5 by said right-angled bends, and oppositely disposed jaws adapted to be either brought together or separated by means of said screw threaded shaft.
2. In an adjustable wrench having a stock 10 and handle formed of a single piece of metal, said stock having a straight portion and a right-angled bend at each end thereof oppositely disposed, the handle portion projecting at right angles to one of said bends 15 and parallel with said straight portion, the combination of a screw threaded shaft journaled in openings in said oppositely disposed bends, and oppositely disposed jaws having angular gripping surfaces.
3. In an adjustable wrench, the combination 20 of a stock and handle formed of a single piece of metal, said stock having a straight portion provided with a longitudinal slot and a right angled bend at each 25 end oppositely disposed, the handle portion projecting at right angles to one of said bends parallel with said straight portion, a double screw-threaded shaft journaled in openings in said oppositely disposed bends, 30 two jaws having oppositely threaded holes through which said screw threaded shaft passes, said jaws being provided with integral shanks extended into said longitudinal slot in the stock and slid able therein whereby 35 said jaws are held in line as they are moved.
4. In an adjustable wrench, the combination 40 of a stock and handle formed of a single piece of metal, said stock having a straight portion provided with a longitudinal slot and a right angled bend at each 45 end oppositely disposed, the handle portion projecting at right angles to one of said bends parallel with said straight portion, a double screw threaded shaft journaled in openings in said oppositely disposed bends, two jaws provided with angular gripping surfaces and having oppositely threaded holes through which said screw threaded shaft passes, said jaws being provided with integral shanks extended into said longitudinal slot in the stock and slid able therein, whereby said jaws are held in line as they are moved, and auxiliary jaws having angular gripping surfaces detachably secured 90 to the ends of said shanks.

Signed by me this 18th day of May, 1914.
LEOPOLD LEER.

shaft passes, said jaws being provided with integral shanks extended into said longitudinal slot in the stock and slid able therein whereby said jaws are held in line as they are moved. 50

5. In an adjustable wrench, the combination of a stock and handle formed of a single piece of metal, said stock having a straight portion provided with a longitudinal slot and a right angled bend at each end oppositely disposed, the handle portion projecting at right angles to one of said bends parallel with said straight portion, a double screw threaded shaft journaled in openings in said oppositely disposed bends, two jaws having oppositely threaded holes through which said screw threaded shaft passes, said jaws being provided with integral shanks extended into said longitudinal slot in the stock and slid able therein, whereby said jaws are held in line as they are moved, and auxiliary jaws detachably secured to the ends of said shanks. 65

6. In an adjustable wrench, the combination of a stock and handle formed of a single piece of metal, said stock having a straight portion provided with a longitudinal slot and a right angled bend at each end oppositely disposed, the handle portion projecting at right angles to one of said bends parallel with said straight portion, a double screw threaded shaft journaled in openings in said oppositely disposed bends, two jaws provided with angular gripping surfaces and having oppositely threaded holes through which said screw threaded shaft passes, said jaws being provided with integral shanks extended into said longitudinal slot in the stock and slid able therein, whereby said jaws are held in line as they are moved, and auxiliary jaws having angular gripping surfaces detachably secured 80 to the ends of said shanks. 85
